UNITED STATES PATENT OFFICE.

GEORGE T. LADD, OF PITTSBURGH, PENNSYLVANIA, ASSIGNOR TO LADD WATER TUBE BOILER COMPANY, OF NEW YORK, N. Y., A CORPORATION OF DELAWARE.

BOILER FURNACE.

Application filed May 24, 1926. Serial No. 111,156.

This invention relates to boiler furnaces, and is particularly useful where the fuel is to be burned in suspension, as, for example, where the fuel is in pulverized form.

8 The invention has to do with that type of boiler which is constructed in the shape of a furnace, and is, in fact, its own furnace.

One of the primary objects of the invention is to simplify the construction, to reduce the number of parts, and to reduce the size of certain parts, whereby the costs are very materially reduced and the size of the installation decreased, as will hereinafter appear, while, at the same time, the installation has a very large capacity, as compared to standard boilers.

I obtain the foregoing, together with such other objects and advantages as may hereinafter appear, or are incident to my invention, by means of a construction which I have illustrated in the preferred form in the accompanying drawings, wherein—

Fig. 1 is a vertical section through a boiler furnace embodying my invention, and

25 Fig. 2 is a vertical section through a modified form of boiler furnace.

Referring now to Fig. 1, the reference character A denotes the boiler furnace considered as a whole, the boiler defining the combustion space proper B, beneath which there is a settling chamber C formed by the setting 3.

The boiler comprises the drums 4 and 5 which may be of the usual diameter, and the headers or small drums 6 and 7; the front water wall a composed of longitudinally finned tubes 8, connected at their upper and lower ends into the upper and lower small drums or headers 6 and 7, respectively; the side water walls b composed of longitudinally finned tubes 9 connected at their upper and lower ends into the upper and lower headers 10 and 11, respectively, the upper headers 10 being connected into the drum 4 and the lower headers 11 being connected into the drum 5; the roof water wall c composed of longitudinally finned tubes 12 connected at one end into the small drum 6, and at the other end into the drum 4; the rear water wall d composed of longitudinally finned tubes 13 connected at their upper and lower ends into the drums 4 and 5, respectively; the bank of tubes 14 connected at one end into the drum 5, and at the other end

into the small drum 7; and the upright bank 55 of tubes 15 connected at their upper and lower ends into the drums 4 and 5, respectively.

In connection with the headers 6 and 7 and the drums 4 and 5, it is pointed out that the 60 headers 6 and 7 are more closely spaced than are the drums 4 and 5, and that the upper header 6 is below the level of the upper drum 4. By this arrangement the tubes 12 of the roof wall c constitute upcomers from the 65 upper header 6 to the upper drum 4, by virtue of which only one upper drum need be employed, and the usual upper steam drum is dispensed with, and, consequently, the cost of the installation is reduced. It will be ob- 70 served that the diameter of the drums 6 and 7 of the front wall may be greatly reduced by this arrangement which further reduces the manufacturing costs of the installation.

The bottom of the combustion chamber B 75 is bounded by the bank of tubes 14, the tubes of which are sufficiently spaced apart to allow any refuse particles precipitating out of the fuel to pass therebetween to the settling chamber C. The precipitating ash is cooled 80 below slag forming temperature by these tubes.

Although the waste gases of combustion, passing through the bank of tubes 14, are cooled somewhat by these tubes, they are 85 not, however, cooled below the temperature required to superheat the steam passing through the superheater 16 located in the path of the waste gases from the chamber C to the offtake 17. The superheater 16 is 90 located between the upright bank of tubes 15 and the rear water wall d of the boiler. The products of combustion, after passing over the superheater elements 16, pass over the bank of tubes 15, suitable baffling being 95 provided to direct the course of the gases. After passing over the bank of tubes 15, the gases pass into the breeching 18, in which a combustion air preheater 19 is located. Thus, it will be seen that the 100 superheater 16 is so located as to be subject to gases of high enough temperature to obtain the proper degree of superheat, and that the air heater is not subjected to gases of such high temperatures as would burn 105 out the elements thereof, because of the introduction of convection surfaces, namely, the bank of tubes 15, between the super-

heater and the air preheater, which tend to pull down the temperature of the gases after they leave the superheater. This arrangement is of great importance, as the 5 gases leave the combustion space proper at relatively very high temperatures, this being necessary in order to secure the most effective results of the radiant heat surfaces which define such combustion space. Without 10 further cooling these gases would be hot enough to destroy the air heater as above pointed out. In addition, the maintenance of high temperatures in the combustion space proper is of great importance in 15 ensuring effective combustion.

The bank of tubes 15 constitutes the economizer section of the boiler, and is an integral part therewith by reason of the tubes connecting at their ends into the 20 drums 4 and 5 of the boiler. The tubes of this bank of tubes become the downcomers of the boiler, the circulation in the tubes of the water walls and in the tubes of the bank of tubes 14 being in an upward direction. Thus, the necessity for the usual 25 outside downcomer tubes with their lagging is obviated, which enables me to decrease the length of the drums, and, consequently, reduce the width of the boiler, and, at the 30 same time, effecting a saving in manufacturing costs. The cost of drums, particularly where the pressures are relatively high, is an important economical factor.

The fuel to be burned is introduced at the 35 four corners of the combustion chambers by means of the burner nozzles 20, preferably located at the upper portion of the combustion chambers. Highly preheated combustion air is introduced with the fuel 40 through the medium of the air openings 21 surrounding the burner nozzles 20, the preheated air being taken from the air heater 19 by the ducts 22 leading to the burners. Thus the fuel and air is introduced 45 in a manner to produce vortical mixture and combustion, the combustion being intense and turbulent, whereby a high flame temperature and short length of flame travel is obtained.

50 Referring now to the modification illustrated in Fig. 2 it will be seen that I have provided what may be termed a double type of boiler furnace, by positioning two boiler furnaces, of substantially the same construction as that shown in Fig. 1, with the front 55 water walls a' , a' , adjacent to one another. However, instead of connecting the lower ends of the tubes of each of the water walls a' into a separate header, I have connected 60 them into a common drum 7^a . The tubes of the side walls b in this instance, as before, are connected at their upper and lower ends into headers, and the upper 65 headers 10 are each connected into their corresponding upper drums 4, but the lower

headers 11^a are connected into the lower central drum 7^a through the medium of the T connection 11^b.

70 Thus, it will be seen that a very compact and simple installation having two combustion chambers largely defined by tubular water walls is provided, in which installation the advantages above pointed out in connection with a single type boiler furnace are present.

75 I claim:—

1. A tubular boiler-furnace having the combustion space primarily defined by tubes subject to radiant heat, the rear wall of said combustion space being formed of an upper drum, a lower drum, and tubes connecting into said drums, the front wall being formed of an upper header, a lower header, and tubes connecting into said headers, said front wall headers being more closely spaced than the rear wall drums the upper header being below the level of the upper drum and the lower header being above the level of the lower drum, tubes connecting the lower drum and lower header, tubes connecting into the upper drum and upper header, and a bank of tubes exterior to the combustion space connecting into the upper drum and the lower drum.

80 2. A tubular boiler-furnace having the combustion space primarily defined by tubes subject to radiant heat, the rear wall of said combustion space being formed of an upper drum, a lower drum, and tubes connecting into said drums, the front wall being formed of an upper header, a lower header, and tubes connecting into said headers, said front wall headers being more closely spaced than the rear wall drums the upper header being below the level of the upper drum and the lower header being above the level of the lower drum, tubes connecting the lower drum and lower header, tubes connecting into the upper drum and upper header, and a bank of tubes exterior to the 85 combustion space connecting into the upper drum and the lower drum, together with means for admitting pulverized coal and combustion air for turbulent combustion, and an offtake for the products of combustion 90 beyond the aforesaid bank of tubes.

95 3. In a pulverized fuel burning installation a boiler comprising a pair of upper drums, a pair of upper headers intermediate but below the level of said drums, a pair 100 of lower drums, a lower drum intermediate and above the level of said pair of lower drums, upright tubes connected into one upper and one lower drum of said pairs of drums, upright tubes connected into the 105 other upper and lower drums of said pairs of drums, upright tubes connected into one header and said intermediate lower drum, upright tubes connected into the other header and said intermediate drum, upright 110

tubes connected with one drum of the upper pair of drums and the intermediate lower drum, upright tubes connected with the other upper drum and said intermediate drum, said upright tubes constituting water walls for the upright walls of two combustion spaces, a roof wall for each combustion space composed of tubes connected into the upper drums and the upper headers, 10 tubes marginal of the bottoms of said combustion spaces connected between the pair of lower drums and the intermediate lower drum, economizer tubes exterior to the combustion space connected into each upper 15 and lower drum of the upper and lower pair of drums, said economizer tubes constituting the sole downcomers for the boiler, means for introducing pulverized coal and combustion air for turbulent combustion 20 into each combustion space, and an offtake for the products of combustion for each combustion space.

5

4. A tubular boiler-furnace having the

combustion space primarily defined by tubes subject to radiant heat, the rear wall of 25 said combustion space being formed of an upper drum, a lower drum, and tubes connecting into said drums, the front wall being formed of an upper header, a lower header, and tubes connecting into said headers, 30 said front wall headers being more closely spaced than the rear wall drums, the upper header being below the level of the upper drum and the lower header being above the level of the lower drum, tubes 35 connecting the lower drum and lower header, tubes connecting into the upper drum and upper header, other tubes connecting the upper and lower drum and constituting the sole downcomers for the boiler and 40 means for shielding said other tubes from radiant heat of the combustion space.

In testimony whereof I have hereunto signed my name.

GEORGE T. LADD.
